UNITED STATES PATENT OFFICE

ALLAN ROLAND PYE JOHNSON, OF TORONTO, ONTARIO, CANADA

AUTOMOBILE STOP-SIGNAL SWITCH BOX AND ATTACHING MEANS THEREFOR

Application filed July 25, 1927. Serial No. 208,308.

My invention relates to improvements in automobile stop signal switch boxes and attaching means therefor, and the object of the invention is to devise a stop light switch box in which tension springs subject to distorting strain are dispensed with, in which means are provided for attaching the switch box to a brake lever of any form, and which will permit of the ready adjustment of the switch box so that the spring pressed plunger thereof will bear squarely against the lower face of the foot board, and it consists essentially of the arrangement and construction of parts as hereinafter more particularly explained.

Fig. 1 is a perspective view of a portion of a foot board and brake lever and my switch box applied thereto.

Fig. 2 is a sectional view through the switch box and brake lever in the normal position and showing diagrammatically the circuit connection to a stop signal casing.

Fig. 3 is a sectional view through the switch box showing the parts in their operative or circuit closing position.

Fig. 4 is a perspective detail of the contact ring employed in my construction.

In the drawing like characters of reference indicate corresponding parts in each figure.

1 indicates a portion of a foot board provided with the usual slot 2. 3 is a brake lever of usual construction. 4 is an arm provided with a portion 4^x straddling over the brake lever. 5 is a clip plate provided with a portion 5^x straddling the opposite side of the brake lever, the portions 4^x and 5^x being connected together by securing bolts 6 and 7.

The inner end of the arm 4 is provided with an upwardly extending portion 8 having an orifice 8^x.

9 is the body of my switch box which is provided at its upper edge with an enlarged internally threaded portion 9^x forming a shoulder 9°. 10 is an orifice formed in the bottom of the casing body 9 centrally thereof. 11 is a disc of fibre or other suitable insulating material which fits within the internally threaded enlarged portion 9^x of the casing body so as to rest upon the shoulder 9°. 12 and 13 are contact screws, the heads of which bear against the lower face of the disc 9^x and provided at

their upper ends with nuts 13^x securing the terminal clips 14 to the contact screws. 15 and 16 are lead wires which are connected by the clips 14 to the contact screws 12 and 13, one of the lead wires 16 leading to the battery 18 and the other lead wire 15 to one terminal of the light source of the stop light casing 20. 21 is a wire leading from the other terminal of the light source to the other terminal of the battery 18.

It will, therefore, be seen that all it is necessary to do to make the circuit through the light source of the stop light indicator is to bridge the contact screws 12 and 13.

22 is the cover of my stop light switch box provided with a reduced externally threaded portion 23 which is screwed into the internally threaded portion 9^x so as to bear upon the outer edge portion of the disc 11, and thereby firmly hold it in position. The wall of the cover 22 is provided with an open ended slot 24 into which the lead wires 15 and 16 may be readily inserted before the cover member 22 is screwed into position, and thereby avoiding the necessity of threading the lead wires through an orifice to pass them to their point of attachment. The cover member 22 is provided with a central orifice 25 in vertical alignment with the orifice 10.

26 is a plunger which slidably extends through an orifice 27 in the disc 9^x and is provided at its lower end with a reduced portion 28 fitting the orifice 10 and at its upper end with a head 29 which normally bears against the lower face of the foot board 1 as clearly indicated in Figures 1 and 2. 30 is a fibre disc provided with a central orifice 31 and side orifices 32 and 33 which are in diametric alignment. 34 is a metallic contact ring fitted upon the upper face of the disc 30 and provided with tongues 35 and 36 extending from the inner edge thereof through the orifices 32 and 33, the extremities of the tongue being then bent outward as indicated at 37 and 38 to bear against the lower face of the disc 30 and thereby securely hold the contact ring 34 in position. 39 is a conical spring surrounding the reduced portion 28 of the plunger 26 and bearing at its lower ends against the bottom of the switch box

body and at its upper end against the central portion of the disc 30 around the orifice 31. 40 is a threaded stem extending from the switch box body 9 through the orifice 8^x of the arm 4 and provided with a securing nut 41.

5 By loosening the nut 41 the switch box may be turned to any desired position so that the plunger 26 will be directly at right angles to the lower face of the foot board 1 independently of the position or set of that portion of the brake lever to which my switch box is attached.

10 It will be readily seen that when the foot brake lever 3 is depressed in the usual manner my switch box will be carried downward and the head 29 of the plunger away from the opposing face of the foot board 1 so as to permit the spring 39 to force the plunger and the disc 30 and contact ring 34 carried thereby upward so that such contact ring will be brought into engagement with the contact screws 12 and 13 and thereby forming a bridging connection therebetween so as to close the circuit.

15 25 When the foot brake is released the opposite operation takes place, that is as the brake lever swings upward the head 29 of the plunger 26 is brought into engagement with the foot board and is thereby depressed against the pressure of the spring 39, thereby carrying the disc 30 and contact ring 34 downward so as to break the connection between the contact screws 12 and 13.

30 35 From this description it will be seen that I have devised a stop light switch box which may be operated without the employment of any springs which are drawn into spring tension and thereby liable to become distorted, preventing the operation of the switch 40 45 box to open and close the circuit by breaking the contact connections, and at the same time I devise a switch box which may be readily adjusted to suit the form of brake lever and location of the foot board with which it coacts, and which may be readily applied to any form of brake lever, the arm of which extends either in a substantially horizontal or substantially vertical direction.

50 45 What I claim as my invention is:—

55 In a stop light switch box, the combination with a supporting bracket, of a casing body formed with an interiorly threaded upper portion terminating in an annular internal shoulder, a cover screw in the body portion and having a central orifice, a plunger extending through the orifice having a reduced lower end, an annular insulating washer mounted upon the upper portion of the plunger within the casing to fit at its edges 60 65 between the shoulder of the casing body and the cover, terminal contact screws mounted in the annular insulating washer, an annular contact washer fitting the lower portion of the plunger having an annular contact surface on its upper face engaging the aforesaid

70 contact screws and a conical spring surrounding the plunger and bearing against the lower face of the contact washer at its upper end and against the bottom of the casing body at its lower end.
